(57) **CLAIM**

We claim, the ornamental design for a sensing mechanism, as shown and described.

DESCRIPTION

FIG. 1 is a perspective view of a sensing mechanism, showing our new design in an exemplary embodiment;

FIG. 2 is a front view of the embodiment shown in FIG. 1;

FIG. 3 is a back view of the embodiment shown in FIG. 1;

FIG. 4 is a side view of the embodiment shown in FIG. 1;

FIG. 5 is another side view of the embodiment shown in FIG. 1;

FIG. 6 is a top plan view of the embodiment shown in FIG. 1;

FIG. 7 is a bottom plan view of the embodiment shown in FIG. 1;

FIG. 8 is a perspective view of a sensing mechanism, showing our new design in another exemplary embodiment;

FIG. 9 is a front view of the embodiment shown in FIG. 8;

FIG. 10 is a back view of the embodiment shown in FIG. 8;

FIG. 11 is a side view of the embodiment shown in FIG. 8;

FIG. 12 is another side view of the embodiment shown in FIG. 8;

FIG. 13 is a top plan view of the embodiment shown in FIG. 8; and,

FIG. 14 is a bottom plan view of the embodiment shown in FIG. 8.

The broken lines are for environmental purpose only and form no part of the claimed design.

The dash-dot lines are boundary lines delineating claimed subject matter within the dash-dot lines from unclaimed, unshaded subject matter outside of the dash-dot lines.

Also, references to “side,” “top,” “bottom,” “front,” and “back” in the Figure Descriptions are not necessarily meant to require any specific orientation of the article as viewed. A molded cover according to the claimed design may be used in any orientation.
